UNITED STATES PATENT OFFICE.

JOHN STEERN, OF NEW YORK, N. Y.

UNDERWAIST.

1,315,350.

Specification of Letters Patent. Patented Sept. 9, 1919.

Application filed September 21, 1916. Serial No. 121,364.

To all whom it may concern:

Be it known that I, JOHN STEERN, a citizen of the United States, residing in the city, county, and State of New York, have 5 invented certain new and useful Improvements in Underwaists, of which the following is a specification.

My invention relates to an article of apparel and particularly relates to a child's 10 underwaist of the type wherein the arm-hole section is doubled to provide reinforced sides extending from the shoulder to the waist portion of the garment.

Such articles are at present constructed in 15 large numbers and in order to place them on the market at the lowest possible price it is necessary to minimize both in material and in the area reinforced and to reduce the necessary operations to the least possible 20 number that will permit the construction of a salable garment and at the same time preserve a fit to the same.

Accordingly, one of the objects of the invention is to provide an article of the class 25 described which can be formed of the least possible amount of material and with the minimum amount of labor.

Practically all of the strain upon articles of this character is on the sides and it has 30 been a desideratum to transmit these strains to the shoulders and to also transmit the same over as broad an area as possible, taking into consideration the economy in use of material.

I have found, however, that when the double sided waist is made of light material, strains on the waist-line has the effect 35 of pulling on the sides of the waist, distorting the same and forming a puckered article 40 which seriously affects its salable quality. This stretching and distorting of the sides, however, can be effectively prevented merely by incorporating a separate insert strip, in the seams, which fastens the reinforcing 45 piece to the main portion of the garment and extending this strip from the waist portion to the shoulder portion of the garment.

Various other objects and advantages of the invention will be in part obvious from 50 an inspection of the accompanying drawings and in part will be more fully set forth in the following particular description of one form of underwaist embodying my invention, and the invention also consists in certain new and novel features of construction

and combination of parts hereinafter set forth and claimed.

Referring to the accompanying drawings:

Figure 1 is a plan view showing a preferred embodiment of my invention and 60 with parts broken away to show internal construction of the reinforced seams; and

Fig. 2 is an enlarged transverse sectional view taken substantially on the line 2—2 of Fig. 1.

The underwaist illustrated includes three main portions, a central back portion 5, opposite side edges 6 and 7 of which are cut away to form parts of the arm holes 8, and to form extensions providing for side portions 9,

extending beneath the arm holes and for shoulder portion 10, extending above the arm holes. Fastened to each of the edges 6 and 7 are two main front portions 11 similarly cut to form shoulder portions 12 and side portions 13 and coacting with the adjacent sides of the back portion to form the arm holes 8, all as is usual with devices of this character. A seam 14 connects the shoulder portions 10 and 12 and a seam 15 connects the side portions 9 and 13 and these forms of seam may be any conventional character of sewing now in general use in devices of this character.

80 To form the double portion of each arm hole section, a reinforcing piece 16 is provided with an opening 17 registering with the correlated arm hole formed in the main portions and tending to reinforce the portions of the

waist above the arm holes. As is usual with 90 devices of this character, the reinforcing piece extends downwardly usually to the bottom of the garment and across the waist-line 18 to reinforce the sides below the arm holes. The reinforcing piece extends over 95

the shoulder portion and may be fastened at the top by means of the seam 14. This reinforcing piece may be made, if desired, of two pieces to insure a better fit with some types of underwaists and in this case the 100

seam 15 may be utilized also to fasten the two parts of the piece together below the arm holes. The outer edge 19 of the reinforcing piece is fastened to the adjacent portion of the back or front portion by 105

means of a line of sewing 20. This line of sewing may be in the form of a filled seam extending from the waist-line to the shoulder portion. The construction thus far de-

scribed resembles a known form of garment 110

but in this case the seam 20 includes an insert 21. This strip may be a single layer but in order to provide an additional reinforcement without materially increasing the thickness of the seam, the strip in the device illustrated is shown to be bent back upon itself longitudinally so as to provide a double thickness to the reinforcing insert.

It is understood that by means of a device of this character it is possible to attain in an underwaist all of the reinforcements incidental to the double thickness of waist at the shoulder portions and beneath the arm holes, and at the same time, to provide an additional reinforcement along the lines where such a reinforcement is most needed; that is, from the waist-line to the shoulder line and spaced on opposite sides of the arm holes. By using merely the small insert strip a material saving is provided in the elimination of extra material for the portion of the waist beneath the arm holes and a construction is provided which will not pucker and which will hold rigidly even when subjected to some material pull between the waist-line and the shoulder portion. The small amount of material to form the insert necessitates but a small additional amount of material, but this small amount is advantageously disposed at a place where the greatest resistance of strain is desired and as a seam is at this place anyhow, the insert does not detract from the appearance of the article. As the insert is spread out over the shoulder no discomfort is noted from its use and as the article is sold it is not even apparent that these seams are any different from other seams such as are present below the arm holes.

It is noted that by this construction there

is provided not only the usual double thickness of material beneath the arm holes but three and even four thicknesses of material are provided along the line of the reinforcement and this is attained with the addition 45 of a negligible amount of additional material.

Having described my invention, I claim:

An underwaist including a main portion formed at one side of a back portion and a front portion cut away at their meeting edges to form an arm hole with a shoulder portion above the arm hole and a waist line below the arm hole, means for transmitting strains on the waist line directly to the shoulder portion, said means including a reinforcing piece extending from the waist line to the shoulder portion and adapted to reinforce the main portion about the arm hole, one edge of said reinforcing piece being fastened to the main portion by means of a flat seam, an insert positioned between the main portion and the reinforcing piece and extending from the waist line to the shoulder portion, said insert having one edge 60 bent back upon itself whereby a double thickness of the insert will extend from the waist line to the shoulder portion to transmit strains along said double thickness, said double thick portion of the insert being concealed in said seam and said insert provided with a single thickness extending laterally from the double thick portion thereby to provide some material width to the insert 70 for distributing the strains on the waist line 75 over a relatively broad area.

Signed at New York city, in the county of New York and State of New York, this 18th day of September, A. D. 1916.

JOHN STERN.
